PORTRABLE DE-MAGNETIZER

Darrel A. Lauer, San Francisco, Calif., assignor to
Ampex Corporation, Redwood City, Calif., a corporation of California

Filed May 16, 1966, Ser. No. 2,310

Term of patent 14 years

(Cl. D26—1)

FIG. 1

FIG. 2

FIGURE 1 is a front, right side and top perspective view of a portable de-magnetizer, showing my new design; and

FIGURE 2 is a rear, left side and top perspective view, the bottom being substantially a mirror image of the top.

I claim:

The ornamental design for a portable de-magnetizer, substantially as shown and described.
